William Baker

UNITED STATES PATENT OFFICE.

WILLIAM BAKER, OF UTICA, NEW YORK.

CLAPBOARD-JOINT.

Specification forming part of Letters Patent No. 10,903, dated May 16, 1854; Reissued September 22, 1863, No. 1,541.

To all whom it may concern:

Be it known that I, WILLIAM BAKER, of the city of Utica, in the county of Oneida and State of New York, have invented a new and useful Improvement in the Preparation and Joining of Clapboards for the Siding of Houses and other Buildings; and I do hereby declare that the following is a full and exact description thereof, reference 5 being had to the accompanying drawings and to the letters of reference marked thereon.

The nature and principal object of my invention is so to construct and form the 15 boards for the siding of houses, that in putting them together and nailing them to the frame of the building the heads of the nails may be covered, while at the same time the chief characteristic of clapboarding, the 20 overlapping of one board upon another for shedding the water, shall be preserved.

In Figure 1 of the annexed drawings A and B represent transverse sections of two 25 of my clapboards as nailed to the frame of the building, showing by the connection of the two at C, the manner in which they are dressed and put together. N, N, is a stud of the building frame showing the manner in 30 which they are laid against the studs to which they are to be nailed.

Fig. 2 is a transverse section of a single board, shown separate from the building, exhibiting the character of the dressing on the respective edges, A being the upper, and 35 B being the lower edge when laid on.

The configuration of the cut a, b, e, in the lower edge of the board, is clearly shown in both figures of the drawings. It is made to correspond to the upper edge A, so that they 40 fit together as seen at the conjunction C, (Fig. 1). The line e, in this cut, is not made directly down the edge of the board parallel to the rear line of the board, but is a little

oblique, corresponding to the front line C; otherwise, it is evident, it would not make 45 a close fit to the other board. The dressing of the upper edge of the board is shown at H.

It is plain that if the board B, (Fig. 1,) is first laid on and nailed near its upper edge, 50 as shown at F, that the lower edge of the next board A, when brought to its place, as shown in the figure, will be held securely by the lock a, without nailing, and that the nail therefore may be driven in this board also at 55 F, near the upper edge, and so on with each successive board. It is also plain that each successive board, by its extended lip D, will cover the heads of the nails driven in the preceding board as here shown. It is proper 60 to make the lip D, about three-fourths of an inch in length, both for the purpose of effectually shedding the water, and to cover the heads of the nails as here described. The lips a, and i, are each about one-fourth 65 of an inch long.

The drawings exhibit the clapboards of the full ordinary width and thickness, and the several members of the joint of the proper relative dimensions substantially. 70

Having thus described my invention, and the objects to be attained by it, what I claim as new, and desire to secure by Letters Patent, is—

The combination of the lock a, in the rear 75 of the joint, with the extended lip D, in front, constructed and used in conjunction, for the purposes of effecting the objects of the invention as specified, the whole being constructed, combined and arranged substantially in the manner and for the purposes herein set forth.

WM. BAKER.
